UNITED STATES PATENT OFFICE

JOHN P. GILBANKS, OF LITTLE NECK, NEW YORK

DESIGN FOR A FLOWER HOLDER

Application filed March 17, 1932. Serial No. 43,214. Term of patent 3½ years.

To all whom it may concern:

Be it known that I, JOHN P. GILBANKS, a citizen of the United States, residing at Little Neck, Long Island, county of Queens and State of New York, have invented a new, original, and ornamental Design for a Flower Holder, of which the following is a specification, reference being had to the accompanying drawings, forming part thereof.

The egg-shaped holder may be given any desirable and appropriate color.

I claim:

The ornamental design for a flower holder as shown and described.

In testimony whereof, I have hereunto set my hand on this 15th day of March, A. D. 1932.

JOHN P. GILBANKS.
